PAINT BRUSH COMB

David R. Darge, Whitehouse Station, N.J., assignor to Red Devil Inc., Union, N.J., a corporation of New Jersey

Filed Jan. 29, 1968, Ser. No. 10,347

Term of patent 14 years

(Cl. D49—23)

FIG. 1

I claim:

The ornamental design for a paint brush comb, substantially as shown.
